UNITED STATES PATENT OFFICE.

JOSEPH FOSSA, OF DANVERS, MASSACHUSETTS, ASSIGNOR TO UNITED SHOE MACHINERY CORPORATION, OF PATERSON, NEW JERSEY, A CORPORATION OF NEW JERSEY.

BUTTONHOLE-SEWING MACHINE.

Application filed April 9, 1920. Serial No. 372,458.

To all whom it may concern:

Be it known that I, JOSEPH FOSSA, a citizen of the United States, residing at Danvers, in the county of Essex and State of Massachusetts, have invented certain new and useful Improvements in Buttonhole-Sewing Machines; and I do hereby declare the following to be a full, clear, and exact description of the invention, such as will enable others skilled in the art to which it appertains to make and use the same.

The invention relates to buttonhole sewing machines in which overseam stitches are formed about the edge of the buttonhole by the cooperation of upper and under-thread mechanisms, and more particularly to means for controlling the under thread.

In sewing a series of buttonholes in a piece of work upon the type of machines to which the present invention more particularly relates the under thread remains attached to the work, and extends from buttonhole to buttonhole along the under surface of the work. In spacing the work the operator, therefore, frequently draws a surplus amount of under-thread through the under-thread tension so that the under-thread is slack at the beginning of the succeeding buttonhole, with a resulting undesirable looseness in the initial stitch or stitches of the seam. The spacing of the work also involves drawing the under-thread through the under-thread tension and in doing certain classes of work, which require a comparatively heavy tension on the under-thread, it has been proposed to release the tension at the completion of the sewing to avoid danger of breaking the thread and the strain on the operator incident to drawing the thread through the tension. This, however, is likely to increase the surplus thread between the completed buttonhole and the under-thread tension, and to objectionably increase the number of loose stitches formed at the beginning of the next buttonhole, since comparatively little of the under-thread enters into each stitch in doing that class of work which requires a heavy under-thread tension.

The present invention avoids or eliminates the objections outlined above by the provision of means for taking up any slack thread between the under-thread tension and the previously sewed buttonhole after the work has been spaced and prior to the sewing of

the initial stitch of the buttonhole seam, and by the provision of means for drawing through the under-thread tension sufficient thread to permit the spacing of the work without releasing the tension for the under-thread. These functions are preferably effected by the same means which, in its preferred form, comprises a thread take-up and pull-off arranged between the under-thread tension and the under needle, and operated at the beginning of a buttonhole making cycle to take up a loop of thread between the tension and needle, and operated at the end of the buttonhole making cycle to give up this loop of thread to provide slack thread between the tension and work which may be freely drawn through the needle in spacing the work. After the work is spaced the take-up and pull-off, in taking up its loop at the beginning of the next buttonhole making cycle, takes up any slack thread between the previously sewed buttonhole and the under-thread tension, and thereafter draws thread through the under-thread tension to be held until again given up at the end of this buttonhole making cycle.

The invention will be readily understood from an inspection of the accompanying drawings and the following detailed description of the mechanism illustrated therein.

In the drawings Fig. 1 is a vertical sectional view showing so much of a buttonhole sewing machine as is necessary to illustrate the application of the present invention thereto. Fig. 2 is a plan view on a larger scale, showing the under-thread mechanism and a part of the clamp carrier. Fig. 3 is a view similar to Fig. 2, showing the parts in a different position, and Fig. 4 is a vertical sectional view on line 4-4, Fig. 2.

In the drawings the invention is shown as embodied in a buttonhole sewing machine having substantially the construction and mode of operation of the machine shown and described in Patents No. 1,063,880, June 3, 1913, and No. 1,134,046, March 30, 1915. In this machine the stitch forming mechanism comprises an upper needle 2, an under needle 4, and a looper 6. The upper needle bar 8 is mounted in a rotary carrier 10, and the under needle and looper are mounted in a rotary turret 12, the carrier and turret being rotated during the sewing about the eye and bar ends of the buttonhole. The

work is held by clamps 14 mounted on supporting plates 16, which are in turn mounted on a clamp carriage 18. The clamp carriage is moved lengthwise of the buttonhole to bring the work from cutting to sewing position and the clamp carriage is moved laterally and the stitch-forming mechanism is rotated by mechanisms fully described in said patents.

10 The under-thread tension is mounted on the turret and comprises two tension disks 20, pressed together by spring 22, the pressure of which may be adjusted to secure the tension requisite for the class of work 15 to be done. The under-thread passes from the hollow link 24, which forms a part of the mechanism for actuating the under needle and looper, between the tension disks, to an eye 26 in the end of a lever 28 and 20 thence to an eye 30 on the needle carrier 32, from which it leads through the eyes of the under needle. The lever is mounted in the turret and its hub surrounds and forms the bearing for the rock shaft 34 25 on which the looper arm 36 is carried. During the sewing the lever is held in position against the stop 38 by a torsional spring 40, as indicated in Fig. 3, and the eye 26 in the lever corresponds to the usual fixed 30 thread guide from which the under-thread leads to the eye on the needle carrier. When the sewing mechanism stops the under needle is brought to rest in its retracted position and the eye 26 holds a loop of 35 thread between the tension and the needle carrier. The lever 28 is actuated to give up this loop and thus provide slack thread for the spacing of the work by the movement of the work clamp carriage from sewing 40 to cutting position at the completion of the buttonhole making cycle. As shown the means for thus actuating the lever comprises a lever 42 mounted on the turret bracket, and arranged to engage an arm 44 projecting 45 from the hub of the lever 28 when the turret is in stopped position. A bar 46 secured to the clamp carriage is arranged to engage and actuate the lever 42. When the sewing mechanism is stopped at the completion 50 of the sewing of the buttonhole the turret is in the position indicated in Fig. 2 and the lever 42 and the bar 46 are in the position indicated in Fig. 3. As the clamp carriage moves from sewing to cutting position the bar 46 engages the lever 42 and swings it into the position indicated 55 in Fig. 2 so that the lever acts on the arm 44 of the lever 28 to move the thread eye 26 from the position of Fig. 3 to the position of Fig. 2 and thereby give up its loop so that sufficient slack thread is provided 60 between the tension and the work to permit free movement of the work into position for the sewing of the succeeding button-hole. At the beginning of the next button-

hole making cycle the movement of the clamp carriage from cutting to sewing position prior to the starting of the sewing operation moves the bar 46 away from the lever 42 so that the lever 28 is moved back into position against the stop 38 by its spring. During the first part of this movement the thread eye 26 in the lever acts as a take-up to take up any slack thread which may remain between the work and the tension disks 75 20 and after any slack thread has been taken it acts as a pull-off to pull thread through the tension. It thus draws a loop of thread between the under needle and under-thread tension to be given up at the end of this 80 buttonhole making cycle in supplying slack thread for the spacing of the work.

While it is preferred to employ the specific construction and arrangement of parts shown and described in embodying the invention in a machine of the patent above referred to, it will be understood that this construction and arrangement is not essential to the broader features of the invention, and may be varied or modified as found 90 desirable or best suited to the construction and arrangement of the cooperating parts in the machine in which it is to be embodied.

What is claimed is:

1. A buttonhole sewing machine having, 95 in combination, upper and under thread mechanism, including an under-thread tension located under the work and means for pulling thread through the tension and giving it up at the completion of the sewing to be drawn forward in spacing the work.

2. A buttonhole sewing machine having, 100 in combination, upper and under thread mechanism, including an under-thread tension, and means for taking up slack thread between the tension and a previously stitched buttonhole before starting the sewing at the beginning of a buttonhole making cycle.

3. A buttonhole sewing machine having, 110 in combination, upper and under thread mechanism, including an under-thread tension, means for pulling thread through the tension prior to the beginning of the sewing, and for giving up slack thread between 115 the work and the tension at the completion of the sewing.

4. A buttonhole sewing machine having, 120 in combination, upper and under thread mechanism, including an under-thread tension, a pull-off, and means for actuating the pull-off to pull thread through the tension prior to the beginning of the sewing and to give it up after the sewing is completed.

5. A buttonhole sewing machine having, 125 in combination, upper and under thread mechanism, including an under needle and an under-thread tension, means for pulling thread through the tension to form a loop between the tension and needle at the begin- 130

ning of a buttonhole making cycle, and for giving up the loop at the end of the cycle to be drawn forward in spacing the work.

6. A buttonhole sewing machine having, 5 in combination, upper and under thread mechanism, including an under-thread tension, a clamp carriage movable before and after the sewing, and a pull-off for the under-thread operated by said movement of 10 the clamp carriage.

7. A buttonhole sewing machine having, 15 in combination, upper and under thread mechanism, including a needle for the under-thread, a turret carrying the under-thread mechanism, an under-thread tension on the turret, a pull-off between the tension and needle, and means for actuating the pull-off to pull thread through the tension and to give it up at the end of the buttonhole making cycle to be drawn through the needle 20 in spacing the work.

8. A buttonhole sewing machine having, 25 in combination, upper and under thread mechanism, including a needle for the under-thread, a turret carrying the under- 30 thread mechanism, an under-thread tension on the turret, a pull-off between the tension and needle, means for actuating the pull-off to pull thread through the tension prior to the sewing, and for actuating it at the end 35 of the buttonhole making cycle to give up said thread to be drawn through the needle in spacing the work.

9. A sewing machine having, in combination, upper and under thread mechanism, 40 a turret carrying the under thread mechanism, an under thread tension on the turret, and means for pulling thread through the tension and for giving it up at the completion of the sewing to be drawn forward in spacing the work.

JOSEPH FOSSA.
